UNITED STATES PATENT OFFICE.

WALTER SCOTT GRAU, OF LEBANON, PENNSYLVANIA.

DESIGN FOR A RADIO LOUD SPEAKER.

Application filed July 13, 1927. Serial No. 22,744. Term of patent 3½ years.

To all whom it may concern:

Be it known that I, WALTER SCOTT GRAU, a citizen of the United States, residing at Lebanon, in the county of Lebanon and State of Pennsylvania, have invented a new, original, and ornamental Design for Radio Loud Speakers, of which the following is a specification, reference being had to the accompanying drawing, forming a part thereof.

Figure 1 is a front elevational view of a radio loud speaker, showing the design, and Figure 2 is a side elevational view of the same.

I claim:—

The ornamental design for a radio loud speaker substantially as shown.

WALTER SCOTT GRAU.
